PHASE MODULATION AND AMPLITUDE
MODULATION RECEIVING SYSTEMMurray G. Crosby, Riverhead, N. Y., assignor to
Radio Corporation of America, a corporation of
Delaware

Application February 18, 1942, Serial No. 431,326

9 Claims. (Cl. 250—27)

My present invention relates to receiving systems of the type adapted to receive phase modulated carrier waves or amplitude modulated carrier waves, and more particularly to receivers of the type utilizing a crystal filter network functioning to provide carrier exaltation and conversion of the phase modulated waves to amplitude modulated waves.

There has been described in the Proceedings of the Institute of Radio Engineers, published in the February, 1939, issue thereof (pages 128, 129 and 130), a receiver of the type wherein a crystal filter is employed in a phase modulation receiver to convert the phase modulated waves into amplitude modulated waves; the crystal filter further functioning to provide carrier exaltation. In that receiver the crystal filter utilizes under-neutralization combined with over-neutralization in a manner described in the aforesaid publication. It is, also, described in the aforesaid publication that the crystal filter may be utilized in connection with amplitude modulated carrier waves thereby providing carrier exaltation, the detector for the amplitude modulated carrier waves in that case being independent of the rectifier for the converted phase modulated carrier waves. Reference is, also, made to my following patents showing phase modulated (PM) and amplitude modulated (AM) receivers wherein over- and under-neutralized crystal filters are employed: U. S. Patent 2,204,575, granted June 18, 1940; U. S. Patent 2,156,376, granted May 2, 1939; and U. S. Patent 2,192,684, granted Mar. 5, 1940.

Special reference is made to my pending application, Serial No. 336,316 filed May 21, 1940, wherein is shown a system of the type disclosed in the present application.

Among the various objects of the present invention is to provide various embodiments of PM and AM receivers utilizing crystal filters employing a four electrode crystal holder connected in a manner to provide an under-neutralized output from one output electrode and an over-neutralized output from the other output electrode whereby back-to-back carrier exaltation may be secured at the detector network.

Still other objects of my invention are to provide various forms of PM-AM receivers employing crystal filters of the over- and under-neutralized type, wherein the piezo-electric crystal element is positioned in a predetermined manner in a four electrode crystal holder.

The novel features which I believe to be characteristic of my invention are set forth with par-

ticularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1 shows one embodiment of the invention,
Figs. 2a and 2b show the characteristics of the
crystal filter,

Figs. 3a to 3d inclusive illustrate graphically
the functioning of the crystal filter,

Fig. 4 shows another, and modified, embodiment
of the invention,

Fig. 5 illustrates a further embodiment,

Fig. 6 illustrates a simplified embodiment of
the invention,

Fig. 7 illustrates a modification of the arrange-
ment in Fig. 6.

Referring now to the accompanying drawings, wherein like reference characters in the different figures designate similar circuit elements, there is shown in Fig. 1 that portion of a superheterodyne receiver of the phase modulation-amplitude modulation type which is essential to a proper understanding of the invention. The abbreviations PM for phase modulation and AM for amplitude modulation will hereinafter be used for brevity. The networks prior to the intermediate frequency (I. F.) transformer 4 are not necessary to a proper understanding of this invention, and, therefore, can be generally referred to. It will be understood that they include the signal collector circuit which is followed by the usual converter whose input circuit may be tuned to the desired carrier frequency. It will be further understood that there may be applied to the tunable input circuit of the converter modulated carrier energy either in the AM broadcast band, or signals which are phase modulated and are in a band of ultra short waves in excess of 40 megacycles (mc.). The converter is a local oscillator

network which operates at frequencies which differ from the input carrier frequencies by the operating I. F. value. A special frequency control tube may be employed as a reactance tube in connection with the local oscillator, and, as those skilled in the art well know, the reactance tube will be adjusted by automatic frequency control (AFC) bias. It will be understood that there may be employed sufficient heterodyning prior to the transformer 4 to bring the carrier frequency of the modulated carrier energy to

50
55

that frequency value which is equal to the operating I. F. value of transformer 4. This is true regardless of whether PM or AM signals are being collected at the signal collector.

Assuming, then, that PM waves or AM waves are applied to the intermediate frequency transformer 4, the primary and secondary circuits of the transformer are each tuned to the operating I. F. value. In the case of PM waves the I. F. value is the carrier, or mid-band, frequency of the applied waves. It is, of course, understood that in phase modulation the carrier frequency is deviated in accordance with the modulation amplitude, but the frequency deviation at the higher modulation frequencies is emphasized. Damping resistors are shunted across each of the tuned circuits of transformer 4 in order to provide a sufficiently wide pass band so that the widest frequency swing of the PM waves may be transmitted with efficiency to the crystal filter network. The crystal filter comprises a piezoelectric crystal 1 which is tuned to the I. F. value. One end of the crystal 1 is positioned between a pair of opposed electrodes 2 and 3, the latter being connected to the opposite ends of the tuned secondary circuit. The opposite end of crystal 1 is positioned between the crystal electrodes 5 and 6. It will, therefore, be seen that the crystal is positioned in a four electrode crystal holder. The electrodes 2 and 5 are connected by the coupling capacity C_1 , while the electrode 6 is connected to the high potential side of the transformer secondary circuit by coupling condenser C_2 .

The tubes 7 and 8 are driver tubes which function to feed the modulated waves to the differential diode detection network. The control grid of tube 7 is connected to the electrode 5, while the control grid of tube 8 is connected to the electrode 6. Normal control grid bias is provided for the control grids 7 and 8 in the usual manner as shown in Fig. 1. The plates of the driver tubes are connected to the primary tuned circuits of a pair of I. F. transformers 10 and 11. The transformer 10 has its primary circuit tuned to the operating I. F. value, while the primary circuit of transformer 11 is also tuned to the operating I. F. value. Each of these primary circuits is shunted by a damping resistor to provide the proper band pass characteristic. The junction of the last mentioned primary tuned circuits is connected to the positive terminal of a direct current source (not shown).

The diodes 12 and 13 are arranged in a differential detection circuit for the detection of the phase modulated I. F. waves. The diode 12 has its anode connected to the high potential side of the secondary tuned circuit of transformer 10. It will be understood that the secondary circuit is tuned to the I. F. value, while the cathode of diode 12 is connected to the low potential side of the secondary circuit through the load resistor 12'. In the same way the diode 13 has its load resistor 13' connected in series with load resistor 12', the anode of diode 13 being connected to the tuned secondary circuit of transformer 11. The secondary circuits of transformers 10 and 11 are connected in series between the anodes of diodes 12 and 13, while the junction of the secondary circuits is connected to the junction of load resistors 12' and 13'. Each of the resistors 12' and 13' is shunted by an I. F. bypass condenser. The cathode end of load resistor 13' is grounded, and the phase modulation voltage is taken off from the cathode end

of resistor 12'. AFC bias for the reactance tube, which has already been referred to at a prior point, is derived from the cathode end of resistor 12'.

5 In order to provide detection of AM waves, when such waves are transmitted through the receiving system, a pair of parallel-connected infinite-impedance detectors are also fed by the driver tubes 7 and 8. Thus, tubes 14 and 15 have their control grids coupled to the opposite sides of the secondary tuned circuits of I. F. transformers 10 and 11. The cathodes of tubes 14 and 15 are arranged so that their detected outputs are taken from series connected load resistors 14' and 15' by means of condensers C_3 and C_4 . The control grid of each of the tubes 14 and 15 is connected to the junction of resistors 14' and 15' through a respective grid-return resistor. The junction of the load resistors 14' and 15' is grounded, and each of the load resistors is shunted 10 by a condenser which bypasses the I. F. current but not the modulation currents. In this way each of tubes 14 and 15 functions as a degenerative plate circuit detector, or what has also 15 been described as an infinite-impedance diode detector. It will be seen that the plates of tubes 14 and 15 are connected to positive potential points of a direct current source. Condenser C_3 and resistor R form an equalizing circuit which 20 attenuates the lower audio modulation frequencies to compensate for the exaltation of these frequencies which is effected by the crystal filter during amplitude modulation reception. The high potential ends of load resistors 14' and 15' are 25 coupled through the modulation coupling condensers C_3 and C_4 to the input terminal of the equalizing condenser C_5 .

30 The crystal filter functions to convert the PM waves into AM waves so that the latter may be detected in the differential diode detection network. It has been found that when a crystal filter of the type in which the holder capacitance is neutralized is operated in the off-neutralized condition, it is capable of converting PM waves into AM waves. The conversion is effected by shifting the phase of the modulation side bands with respect to the carrier.

35 Figs. 3a to 3d show the manner in which the crystal filter functions to perform the conversion for a given instant of time. The vector relations between the carrier and side frequencies in an AM wave are as shown in Fig. 3a. The carrier is denoted by the vector C and the upper and lower modulation side bands are denoted by the 40 letters U and L respectively. The phase relation of the three components is such that as the side band frequencies rotate with respect to the carrier vector, they combine with the carrier in a manner to add and subtract from the carrier amplitude and thereby vary the resultant amplitude sinusoidally.

45 The relation of the carrier and side frequencies in a PM wave for a given instant of time is shown in Fig. 3b. It will be seen that the carrier of the PM wave is shifted 90 degrees with respect to that of the AM wave. In view of this phase relation existing between the carrier and side frequencies of a PM wave, it can be seen that the PM wave can be converted into an AM wave for 50 subsequent detection by phase shifting the carrier with respect to the side bands, or by phase shifting the side bands with respect to the carrier.

55 Normally, if there were no capacity coupling between electrodes 2 and 5 of the crystal filter

the filter characteristic obtained between electrodes 2-3 and 5-6 would be a simple resonance curve. However, with the capacity coupling effected by condenser C₁, an over-neutralized filter characteristic is obtained. The operation is similar to the usual neutralized crystal filter which produces a simple resonance curve if the holder capacity is completely neutralized, but produces a characteristic with a maximum output point and a minimum, or rejection, point when neutralization is not perfect. The filter characteristic obtained from electrode 6 may be under-neutralized by means of condenser C₂. Since there is a 180 degree phase reversal between electrodes 5 and 6, the modulated wave energy coupled from the high side of the transformer secondary to electrode 6 by condenser C₂ produces an under-neutralizing effect, whereas the energy transmitted through condenser C₁ produces an over-neutralizing effect.

Figs. 2a and 2b respectively show the under-neutralized characteristic and the over-neutralized characteristic. The under-neutralized characteristic causes the PM wave represented by Fig. 3b to be converted to the vector relations shown in Fig. 3c. The side frequencies in the vicinity of the rejection frequency in Fig. 2a are substantially eliminated so that for these lower modulation frequencies the phase modulation is converted to amplitude modulation by the removal of one side band. The side frequencies in the immediate vicinity of the mid-band, or center, frequency are exalted with the carrier so that an increased output might be expected from these modulation frequencies. On the other hand, due to the over-neutralized characteristic due to condenser C₁, the PM wave is converted into an AM wave as shown in Fig. 3d. It will be understood that in this case the side bands are shifted 90 degrees with respect to the carrier, but in a direction opposite to that effected by the under-neutralized characteristic. The amplitude envelopes are 180 degrees out of phase, and the detected outputs must, therefore, be combined with a 180 degrees phase reversal between them so as to make the outputs additive. This combination cancels amplitude modulation present on the applied PM wave. The phase reversal is effected by grounding the cathode of diode 13, and making the other cathode the high potential point.

Resistors R' and R₁ form output impedances which can be varied to obtain different degrees of selectivity from the two crystal filters. The condensers C₁ and C₂ are shown as actual condensers which may aid or oppose the natural holder capacities. I have found that the natural holder capacities can be adjusted by properly positioning the metal electrodes 2 and 3, 5 and 6 so as to obtain the desired capacities necessary to provide the coupling capacities C₁ and C₂ without the addition of external condensers. Since these electrode plates are near to each other they have an appreciable natural capacity. By properly proportioning the sizes of metal electrodes 2 and 5, the natural capacity between them may be made equal to the desired neutralizing capacity C₁ thereby making it possible to dispense with an external condenser. Also, by properly proportioning the sizes of plates 2 and 6, the natural capacity between them can be made equal to the capacity of C₂ thereby making it possible to dispense with an external condenser between plates 2 and 6. For this type of crystal holder a simple filter is provided which

does not need adjustment with regard to neutralization.

A feature common to the system of Fig. 1, and the circuits of Figs. 4 to 7, is the four-electrode crystal filter. This filter is novel in that an over-neutralized and an under-neutralized filter output may be obtained without the requirement of a push-pull tuned transformer feeding the filter. One side of the secondary of transformer 4 is grounded, whereas in my prior circuits shown in the aforesaid Patent No. 2,204,575 it was mid-tapped. The reason for the push-pull secondary of the last-mentioned prior circuits is to obtain opposite-phase energy for neutralizing. 10 In the present circuits, common-phase energy is applied to the neutralizing condensers C₁ and C₂, but by employing this four-electrode holder the phase of the energy fed through the crystal at terminal 5 is opposite to that from terminal 6.

In Fig. 4 there is shown a modification of the system of Fig. 1. In this modification it is assumed that the I. F. energy produced in the output circuit of a first converter is to be reduced to a second, and lower, I. F. value. In other words, the receiver may be a superheterodyne of the triple detection type. In that case, the converter 100 has its input grid 100' connected to the output circuit of the first I. F. 20 network, while its plate has in circuit therewith the tuned primary circuit of the transformer 111. It will be understood that each of the primary and secondary circuits of transformer 111 is to be tuned to the second I. F. value, and that 30 the latter is substantially lower than the first I. F. value. The remainder of the converter 100 is well known to those skilled in the art. The cathode and first two cold electrodes are connected to provide a local oscillator network 35 which produces oscillations whose frequency differs from the first I. F. by the second I. F. value. The numeral 106 designates the tank circuit of the oscillator section of converter 100.

The numeral 101 denotes a stage of amplification for the second I. F. energy, and those skilled in the art are fully aware of the construction of that amplifier stage. The output electrodes of amplifier 101 are coupled to the crystal filter 113 by the transformer 112 whose primary and 45 secondary circuits are each tuned to the second I. F. value. It will be understood that the primary and secondary circuits of each of transformers 111 and 112 are to be so constructed and arranged that each of them passes the entire frequency range of the transmitted waves.

The crystal 113 is of the type in which the inherent electrode capacities produce the proper degrees of neutralization. As explained previously in connection with crystal 1 of Fig. 1, the natural holder capacities can be adjusted by 60 properly positioning the electrodes so as to obtain the desired capacities corresponding to C₁ and C₂ of Fig. 1. It is to be understood that the crystal filter 113 is such a filter network. As 65 shown in connection with Fig. 1, the input electrodes 130 and 131 are connected to the opposite sides of the tuned secondary circuit 112', the lower input electrode 131 of the crystal filter being grounded. The output electrodes 132 and 133 of the crystal filter are connected to the respective input grids 120' and 121' of the pair of triodes disposed in detector tube 102. These triodes of tube 102 are connected as infinite-impedance diode detectors. Thus, the 70 cathodes of both triodes are connected to ground

through separate load resistors 120 and 121, each of these load resistors being bypassed for I. F. currents but not for modulation voltage, whereby degenerative feedback of modulation voltage is provided to the control grids 120' and 121'.

The resistive path 122 is connected between the control grids 120' and 121', the mid-point of the resistive path being grounded. Resistive path 122 is connected between the crystal output electrodes 132 and 133. The plates 134 and 135 of the triodes of tube 102 are each connected to points of positive potential of a direct current source, and the modulation is derived from across the resistor loads 120 and 121. The modulation voltage is fed in push-pull fashion to the control grids 137 and 138 of the twin triode tube 103. Tube 103 has two separate triode sections whose cathodes are connected in common to ground through the customary bypassed grid biasing resistor 136. The control grids 137 and 138 of the triodes are returned to ground through respective resistors 139 and 140. Grid 137 is connected to the cathode end of load resistor 120 by condenser 141, while grid 138 is connected to the cathode end of load resistor 121 by condenser 142. The transformer 114 is located in the common output circuit of modulation amplifier 103. The transformer 114 has two primary windings 115 and 146. Winding 145 is located in circuit with plate 143 of tube 103. Plate 144 of the tube 103 is connected by lead 150 to terminal 151 of double pole-double throw switch S. The latter is schematically represented. Winding 146 may be connected in either push-pull or push-push relation with winding 145 by suitable adjustment of switch S. When terminals 153 and 154 of winding 146 are connected to respective terminals 152 and 151 of switch S, the +B terminal feeds directly into the junction of windings 145 and 146 and the push-pull connection exists. When switch S is adjusted to connect terminals 155 and 156 of winding 146 to respective terminals 152 and 151, then the windings 145 and 146 are in push-push relation. The secondary winding 147 of transformer 114 feeds a pair of separate output jacks 115 and 116. For phase modulation reception transformer 114 is connected in the push-pull connection by means of switch S, and the modulation output is taken from the jack 115. For amplitude modulation reception switch S is thrown to the push-push connection, and the modulation output is taken from jack 116 after passage through the equalizing circuit C₅-R shown within the dotted square 160.

Automatic frequency control of the oscillator tank circuit 106 is provided by means of reactance-simulation tubes 104 and 105. These reactance tubes are connected in a push-pull circuit with their plate circuits common so that the reactive effects aid in varying the tuning of oscillator 106. This type of push-pull reactance circuit has been described in my application Serial No. 311,074, filed December 27, 1939, granted April 7, 1942, as U. S. Patent No. 2,278,429. The tuned circuit 108 is resonated to the frequency of circuit 106 so that the tuned circuit 108 has a resistive effect. Condenser 118 is adjusted to have a high reactance in comparison to the resistive effect of tuned circuit 108. This results in a current which is capacitive, and the voltage drop across the tuned circuit 108 is in phase with the current and, therefore, feeds a lagging voltage to the grid of tube 104. Amplification of this lagging voltage produces an inductive effect in

the plate circuit of tube 104, because the plate current is caused to lag the applied voltage.

The voltage fed to the grid of tube 105 from tuned circuit 108 is shifted in phase 180 degrees with respect to that fed to tube 104. This causes the grid voltage to lead the plate voltage, with the result that the plate circuit acts as a capacity since the current leads the applied voltage. Hence, when differential control potentials are fed from the time constant circuits 109-110 the inductance of tube 104 is caused to decrease at the same time that the capacity of tube 105 is caused to decrease. The resultant effects of the two tubes 104 and 105 therefore aid, and in this case would increase the frequency of oscillation of tuned circuit 106.

As shown in Fig. 4, the automatic frequency control potentials are derived from the cathode ends of resistors 120 and 121. The time constant resistors 109 and 109' are included in the respective automatic frequency control leads to the control grids of tubes 104 and 105. The coil of circuit 108 is a split coil. The AFC leads are connected through resistors 109 and 109' to the adjacent ends of the split windings of circuit 108. The plates of tubes 104 and 105 are connected in common to the positive terminal of a source of direct current through coil 107, and the high potential side of circuit 106 is connected to the plate side of choke 107 through the coupling condenser 107'. It is believed that the operation of the circuit shown in Fig. 4 will be clear from the description given in connection with Fig. 1.

The receiver modification shown in Fig. 5 is a circuit performing the same functions as the circuit of Fig. 4. In this circuit the crystal filter network is designated by numeral 201, and the output electrodes of that crystal filter feed the diodes 202 and 203 directly. In this circuit the transformer 200 feeds the second I. F. energy from the converter, while the diode anodes are connected to each other through series resistors 204 and 205. The junction of these latter resistors is connected to the junction of cathode resistors 204' and 205'. Resistors 207 and 208 are connected in shunt across resistors 204' and 205', the junction of the resistors 207 and 208 being established at ground potential.

Each of resistors 204' and 205' is bypassed for I. F. currents, and the junction of these two resistors is connected to ground through the condenser 206. It will, therefore, be seen that the ground on the mid-point of the diode resistors is made through condenser 206 and the mid-point of resistors 207 and 208. This method of grounding the diodes removes the permanent bias, which is present on the diode resistors, from the grids of the reactance-simulation tubes 220 and 221. In the normal in-tune, or balanced, condition of the diode currents there will be no current flow through resistors 207 and 208. Therefore, there will be no bias fed to the grids of tubes 220 and 221. If the ground point was placed at the mid-point of the diode resistors, or condenser 206 were short-circuited, the direct current potential across the diode resistors would be fed to the grids of tubes 220 and 221 to give them a permanent bias.

Amplifiers 209 and 210 combine the modulation output in push-pull for phase modulation reception, and the phase modulation voltage is taken off from jack 211. Amplifiers 212 and 213 combine the detected outputs of diodes 202 and 203 in push-push relation, and make them available on jack 214. For amplitude modulation recep-

tion the equalization of the lower modulation frequencies is produced by means of series condensers 222 and 223 and shunt resistors 224 and 225. The automatic frequency control potentials are fed to the reactance tubes 220 and 221 through resistors 216 and 217 respectively and condensers 218 and 219 which form time constant circuits to remove modulation potentials from the reactance tubes. These reactance tubes are connected in this case through resistance-capacity phase shifters 240, 241 and 250, 251.

Thus, the plates of tubes 220 and 221 are connected in common to the positive terminal of the direct current source through the choke 107. The plate of tube 221 is connected to the grounded end of its cathode biasing resistor through the phase shifter path 240, 241. In the same way the plate of tube 220 is connected to its grounded cathode biasing resistor through the phase shifter 251, 250. The automatic frequency control bias is applied to the control grids of each of tubes 220 and 221. Thus, the time constant resistor 217 is connected to the lower end of grid leak resistor 241', while the time constant resistor 216 is connected to the end of the phase shifter resistor 250 adjacent condenser 219. It will be understood that the plates of tubes 220 and 221 are connected across the tank circuit 106 in the same manner as shown in connection with Fig. 4.

Tube 221 produces an inductive effect in its plate circuit, since resistor 240 is adjusted to be large in comparison to the reactance of condenser 241 so that the grid voltage lags the voltage applied from the plate of tube 221. Tube 220 produces a capacitive effect in its plate circuit, since condenser 251 is adjusted to have a large reactance in comparison to resistor 250 so that the grid voltage leads the voltage applied from the plate circuit of tube 220. The detection arrangement shown in this figure is a most practical one.

In Fig. 6 there is shown a self-neutralized type of crystal filter 301 connected to a pair of voltage-doubling diodes 302 and 303. Thus, the transformer 300 may have its primary and secondary circuits each tuned to the operating intermediate frequency, and it is to be understood that this value may be in the megacycle or kilocycle range. The input electrodes of crystal filter 301 are connected to opposite sides of the secondary circuit 300', the low potential side of the latter being at ground potential. Tube 302 may be a 6H6 type of double diode. In that case the anode of one diode and the cathode of the other are connected together, and are coupled to the output electrode 306 through the coupling condenser 307. In the same way, the cathode of one diode and the anode of the other diode of tube 303 are connected in common to the output electrode 306' of the crystal filter through coupling condenser 307'.

The cathode 310 of the diode whose anode is connected to coupling condenser 307 is connected to the cathode 311 of the diode whose anode is connected to coupling condenser 307'. In the same way, the anode 320 of the diode whose cathode is connected to the coupling condenser 307 is connected to the high potential end of output resistor 304. The anode 321 of the diode whose cathode is connected to coupling condenser 307' is connected to the high potential end of load resistor 305. The junction of resistors 304 and 305 is grounded, and each of these load resistors is bypassed for I. F. currents. It will be noted that in Fig. 6 the separate output terminals of

the crystal filter feed the diodes 302 and 303 which are connected individually in voltage-doubling circuits. The detected outputs appear across resistors 304 and 305. Phase modulation voltage, or AFC potential, is obtained from the differentially connected resistors 304 and 305. It will be seen that amplitude modulation can be obtained from these same terminals by the method shown in Fig. 4. Here, again, the crystal filter 301 is of the type shown in Fig. 1, except that the capacities C_1 and C_2 are provided by the natural crystal holder capacity as previously explained.

The arrangement shown in Fig. 7 is a modification of that shown in Fig. 6. Here the self-neutralized type of crystal 301 is arranged to feed a pair of diodes 402 and 403 having cathode load resistors 404 and 406 arranged in series. The junction of these cathode resistors is connected to the junction of series resistors 407 and 408, the latter being connected between the output electrodes 306 and 306' of the crystal filter. The cathode end of resistor 406 is grounded, while each of the cathode resistors is bypassed for I. F. currents. The PM voltage output and the AFC potential are taken off from the cathode end of resistor 404. In other words, the diodes 402 and 403 are connected differentially. This type of connection is convenient for single-ended amplification of the PM voltage output, and for the application of the automatic frequency control potentials to a single reactance-simulation tube.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In combination, a tuned input circuit resonant to the frequency of applied phase modulated carrier waves, a detector network comprising at least two demodulator tubes having respective load resistors arranged in the space current paths of the demodulator tubes, a crystal filter network comprising a piezo-electric crystal, a pair of opposed electrodes having one end of said crystal located therebetween, said electrodes being connected to opposite sides of said input circuit, a second pair of electrodes having the opposite end of said crystal located therebetween, the electrodes of said second pair being connected to respective input electrodes of said demodulator tubes, and the electrodes of said crystal filter being arranged to provide sufficient self-neutralization to produce conversion of the phase modulated carrier waves into corresponding amplitude modulated carrier waves.

2. In combination, a tuned input circuit resonant to the frequency of applied phase modulated carrier waves, a detector network comprising at least two demodulator tubes having respective load resistors arranged in the space current paths of the demodulator tubes, a crystal filter network comprising a piezo-electric crystal, a pair of opposed electrodes having one end of said crystal located therebetween, said electrodes being connected to opposite sides of said input circuit, a second pair of electrodes having the opposite end of said crystal located therebetween, the electrodes of said second pair being connected to respective input electrodes of said demodulator tubes, and the electrodes of said crystal filter

being arranged to provide sufficient self-neutralization to produce conversion of the phase modulated carrier waves into corresponding amplitude modulated carrier waves, means for deriving modulation voltage from across said load resistors, and additional means arranged in push-push relation for deriving modulation voltage from across said load resistors when amplitude modulated carrier waves are applied to said crystal filter input circuit.

3. In combination with a phase modulated carrier input circuit, a demodulator network provided with push-pull arranged input circuits, a crystal filter network for converting phase modulated waves into amplitude modulated waves suitable for detection, said crystal filter comprising a piezo-electric crystal and two pair of holder electrodes, said crystal having its opposite ends disposed between the spaced electrodes of each of said two pair of holder electrodes, means connecting the spaced electrodes of one of said pair of holder electrodes to opposite sides of said phase modulation input circuit, means for connecting the spaced electrodes of the second pair to respective ones of said demodulator input circuits, means providing sufficient capacity between an electrode of said phase modulation input pair of holder electrodes and one electrode of the second pair of electrodes to produce under-neutralization, and additional means providing sufficient capacity between the aforesaid phase modulation input holder electrode and the second electrode of said second pair of electrodes to produce over-neutralization.

4. In combination with a phase modulated carrier input circuit, a demodulator network provided with push-pull arranged input circuits, a crystal filter network, for converting phase modulated waves into amplitude modulated waves suitable for detection, comprising two pair of holder electrodes, a piezo-electric crystal having its opposite ends disposed between the spaced electrodes of each of said two pair of holder electrodes, means connecting the spaced electrodes of one of said pair of holder electrodes to opposite sides of said phase modulation input circuit, means for connecting the spaced electrodes of the second pair to respective ones of said demodulator input circuits, means providing sufficient capacity between two of said holder electrodes to produce under-neutralization, additional means providing sufficient capacity between one of said two electrodes and a third of the holder electrodes to produce over-neutralization, and additional means to provide the demodulation of amplitude modulated carrier waves upon the application of such modulated waves to said crystal filter input circuit.

5. In combination, a modulated carrier wave input circuit having one side thereof at an invariable potential, two demodulator tubes having respective load resistors arranged in the space current paths of the demodulator tubes, a crystal filter network comprising a piezo-electric crystal, a pair of opposed electrodes having one end of said crystal located therebetween, said electrodes being connected to opposite sides of said input circuit, a second pair of electrodes having the opposite end of said crystal located therebetween, means to couple the electrodes of said second pair to respective input electrodes of said demodulator tubes, and separate external neutralizing condensers connected from each of the second pair of electrodes

to the electrode of the first pair connected to the high potential side of said input circuit.

6. In combination with a phase modulated carrier input circuit, a demodulator network provided with a pair of diodes having push-pull arranged input circuits, a crystal filter network for converting phase modulated waves into amplitude modulated waves suitable for detection, said crystal filter comprising a piezo-electric crystal having its opposite ends disposed between the spaced electrodes of each of two pair of holder electrodes, means connecting the spaced electrodes of one of said pair of holder electrodes to opposite sides of said phase modulated input circuit, one side of said input circuit being grounded, means for connecting the spaced electrodes of the second pair to respective ones of said demodulator input circuits, a condenser connected between one of the second pair of electrodes and the ungrounded electrode of said first pair for providing sufficient capacity to produce under-neutralization, a second condenser connected between the remaining electrode of the second pair and said ungrounded electrode providing sufficient capacity to produce over-neutralization.

7. In combination with a source of phase modulated carrier waves, a crystal filter network for converting the phase modulated carrier waves into amplitude modulated waves, a push-pull diode detector network for deriving modulation voltage from the converted modulated carrier waves, said source consisting of a resonant input circuit, said filter network comprising a piezo-electric crystal, a pair of input electrodes and a pair of output electrodes, said crystal having its opposite ends located between said two pairs of electrodes, said input pair being connected to opposite sides of said input circuit, means coupling said detector network to said output electrodes, and separate condensive coupling from each of the output electrodes to a common side of said input circuit.

8. In combination with a phase modulated carrier input circuit, a demodulator network provided opposed diodes having push-pull arranged input circuits, a crystal filter for converting phase modulated waves into amplitude modulated waves suitable for detection, said crystal filter comprising a piezo-electric crystal having its opposite ends disposed between the spaced electrodes of each of two pair of holder electrodes, means connecting the spaced electrodes of one of said pair of holder electrodes to opposite sides of said phase modulated input circuit, means grounding one side of the input circuit, means for connecting the spaced electrodes of the second pair to respective ones of said demodulator input circuits, means providing sufficient capacity between an electrode of the second pair and the ungrounded electrode of the first pair to produce under-neutralization, additional means providing sufficient capacity between the other electrode of the second pair and the ungrounded electrode to produce over-neutralization, and additional means to provide the modulation of amplitude modulated carrier waves upon the application of such modulated waves to said crystal filter input circuit.

9. In combination, a tuned input circuit resonant to applied phase modulated carrier waves, a detector network comprising at least two diode demodulator tubes having respective load resistors arranged in series in the space current paths thereof, a pair of resistors arranged in

series between the diode anodes, the junctions of the load resistors and said pair being connected, a crystal filter network comprising a piezo-electric crystal, a pair of opposed electrodes having one end of said crystal located therebetween, said electrodes being connected to opposite sides of said input circuit, means grounding one side of the input circuit, a second pair of electrodes having the opposite end of said crystal located therebetween, the electrodes of said second pair being connected to respective opposite ends of said pair of resistors, and the electrodes of said

5 crystal filter being arranged to provide sufficient self-neutralization to produce conversion of the phase modulated carrier waves into corresponding amplitude modulated carrier waves, resistive means in shunt with the load resistors for deriving modulation voltage from across said load resistors, and additional means connected to said last resistive means for deriving modulation voltage from across said load resistors when 10 amplitude modulated carrier waves are applied to said crystal filter input circuit.
